(57) CLAIM

The ornamental design for a watch case, as shown and described.

DESCRIPTION

FIG. 1 is a top view of the watch case.

FIG. 2 is a bottom view of the watch case.

FIG. 3 is a side view from the bottom of FIG. 1.

FIG. 4 is a side view from the top of FIG. 1.

FIG. 5 is a side view from the left of FIG. 1.

FIG. 6 is a side view from the right of FIG. 1; and,

FIG. 7 is a perspective view of the watch case.

The broken line showing is for environmental purposes only and forms no part of the claimed design.

1 Claim, 3 Drawing Sheets
